SHAVING SOAP STICK LATHER CUP

Benjamin F. Johnson, Baltimore, Md.

Application July 13, 1933, Serial No. 680,293

1 Claim. (Cl. 45—136)

This invention relates to improvements in soap lather cups for shaving purposes, and more particularly to an improved lather cup adapted to be used with a stick of shaving soap, and to be supported on the soap stick by suitable resilient means incorporated in the body of the lather cup.

An object of the invention is to provide an improved shaving soap stick lather cup preferably bowl-shaped and having a depending cylindrical body portion provided with a plurality of spaced slits, whereby the material of the body portion will have a tendency to spring in to positively engage a soap stick when in the body portion, to hold the same in the desired position.

Another object of the invention is to provide an improved shaving soap stick lather cup preferably bowl-shaped and having a depending cylindrical body portion provided with integrally formed resilient soap stick engaging means, whereby a stick of shaving soap may be supported in the said body portion at the desired height to permit a shaving brush to wipe over the upper end thereof as the brush is wiped about the inner wall of the bowl.

A further object of the invention is to provide an improved one-piece shaving soap stick lather cup, reinforced at its opposite ends with a bead and having suitable soap stick engaging means for positively engaging the stick when in the body portion of the cup.

Other objects will appear as the description proceeds.

In the accompanying drawing which forms a part of my application,

Figure 1 is a side elevation of my preferred form of lather cup applied to a stick of shaving soap;

Figure 2 is a transverse sectional view through the cup and soap stick;

Figure 3 is a sectional view on the line 3—3 of Figure 1;

Figure 4 is a perspective view of my improved form of shaving soap stick lather cup;

Figure 5 is a side elevation of a modified form of shaving soap stick lather cup;

Figure 6 is a transverse sectional view through the lather cup and soap stick illustrated in Figure 5;

Figure 7 is a sectional view taken on the line 7—7 of Figure 5, and

Figure 8 is a sectional view taken on the line 8—8 of Figure 5.

Like characters of reference are used throughout the following specification and the accompanying drawing to designate corresponding parts.

In carrying out my invention, I provide an improved shaving soap stick lather cup formed from a single blank of metal and comprises a bowl portion 1 and a depending cylindrical body portion 2. The annular edges of the bowl portion

1 and the body portion 2 are provided with the peripheral reinforcing beads 3 and 4, respectively.

In Figures 1 to 4, inclusive, I have shown the lower end of the body portion 2 provided with a plurality of tapered slots 5 which are wider 65 in breadth at their inner or upper ends than at their lower or outer ends, which extend through the reinforcing bead 4. The portions of the body between the slots 5 are somewhat tensioned due to their being bent inwardly, so 70 that when a stick of shaving soap 6 is inserted within the body portion 2, said portions will engage the surface of the stick and hold it in the desired position within the body portion 2. It will be apparent that the portion of the body 2 between the slots 5 and the bowl 1 is of sufficient 75 length to provide a suitable bearing or support for the soap stick when in position in the cup.

In Figures 5 to 8, inclusive, I have illustrated a slightly modified form of lather cup, which comprises a bowl portion 7 and a depending body portion 8, which are provided with peripheral reinforcing beads 9 and 10, respectively. In this form of cup, I have provided a plurality of upwardly and inwardly directed resilient soap stick 85 engaging fingers 11 stamped from the body portion 8, and adapted to extend through the openings 12 in the body portion 8. The sectional view illustrated in Figure 8 clearly represents the manner in which the soap stick is engaged and 90 held in the desired position by the resilient fingers.

In both forms of shaving soap stick lather cup, the soap stick will be fed upwardly a slight distance into the bottom of the bowl, as the soap is 95 used. It will be apparent that the cup and soap may be instantly rinsed off under a faucet to clean the same, and when placed in an upside-down position on a shelf, will keep the soap sanitary and prevent it from souring, as much stick 100 soap is wasted in this manner.

Many minor changes in detail may be resorted to without departure from the spirit of the invention.

Having thus described my invention what I 105 claim as new and desire to secure by Letters Patent of the United States is:

A combined shaving soap stick holder and lather cup, comprising an integrally formed concave lather cup having a reinforced peripheral 110 outer edge, and a depending tubular elongated soap stick holder and handle portion arranged axially of said lather cup, and a plurality of resilient soap stick engaging fingers stamped from said handle portion intermediate the ends thereof 115 and having means at their outer extremities for positively engaging a soap stick when in the handle portion to retain the same in the desired adjusted position.

BENJAMIN F. JOHNSON. 120
